UNITED STATES PATENT OFFICE.

PAUL KRÜGER, OF ESSEN, GERMANY, ASSIGNOR TO FRIED. KRUPP AKTIENGESELLSCHAFT, OF ESSEN-ON-THE-EUHR, GERMANY.

LOCKING MECHANISM FOR THE DOORS OF SELF-DISCHARGING RECEPTACLES.

1,423,120.

Specification of Letters Patent.

Patented July 18, 1922.

Application filed October 14, 1921. Serial No. 507,735.

To all whom it may concern:

Be it known that I, PAUL KRÜGER, residing at Essen, Germany, a citizen of the German Republic, have invented a certain new and useful Improvement in Locking Mechanism for the Doors of Self-Discharging Receptacles, of which the following is a specification.

This invention relates to self-discharging receptacles in which the discharging opening is formed by two doors. The object of the invention is to provide a very simple and convenient means for locking said doors in their closed position and this in such a manner that the elements, attached to the doors, of the mechanism for operating the discharge doors are considerably relieved of strain.

An embodiment of the subject-matter of the invention is illustrated by way of example in the accompanying drawing in which—

Figure 1 is an end elevation partially in section of a self-discharging car in the loading position and

Figure 2 is a detail of Figure 1 on an enlarged scale.

For the operation of the two discharge doors A, connecting rods B are provided which are connected by bolts a¹ to the respective discharge door, and carry crank arms b¹ provided with crank pins b². These crank pins b² are adapted to engage in an elongated hole c¹ in a bolt C which is mounted by means of another elongated hole c² on a pin a² of the corresponding discharge door A. The bolts C pass through rectangular slots a⁴ (see Figure 2) provided in the webs of U-irons a³ attached at the free edges of the discharge doors A. The bolts C further have noses c³ intended to catch, in the loading position, over one of the flanges of the U-iron a³ of the other discharge door and thereby lock the two doors to each other.

In the loading position of the car the parts assume the relative position shown in the drawing. In this position each discharge door is supported by means of one flange of the U-iron connected to it on the noses c³ of the bolts C mounted on the other door. The bolts C bear the pressure which is exerted on the discharge doors by the weight of the load and transmit only a comparatively

small turning moment to the connecting rods B, so that these latter are subjected to only a slight strain, the bolts C bearing, under the pressure of the forces acting on them against the pins a² at the upper ends of the elongated holes c².

When the car is being transferred to the discharging position the crank arms b¹ of the connecting rods B rotate in the direction of the arrow x (see Figure 2). This rotary movement is transmitted to the bolts C, so that their noses c³ become lifted off the flanges of the U-irons a³ and thus release the discharge doors. During the rotation of the bolts C the elongated holes c² firstly retain their position, relatively to the pins a² shown in the drawing. In the further course of their rotation the bolts C strike against the lower edge of the slots a⁴ in the U-irons a³, after which the bolts continue to rotate in such a way that the elongated holes c² are shifted relatively to the pins a². The advantage of the arrangement is that the slots a⁴ need only be of slight height so that only the webs of the U-irons a³ need be provided with a recess.

The manner in which the mechanism works when returned into the loading position requires no description beyond that already given above.

I claim:

1. In a locking mechanism for doors, an operating element for each door, a bolt pivotedly secured to each door and pivotedly secured to the associated operating element, each bolt engaging in the loading position of the doors behind the edge of the other discharge door.

2. In a locking mechanism for the doors of self-discharging receptacles, discharge doors, an operating element pivotally mounted on each door, a bolt for each door, means pivotally connecting each operating element to its associate bolt, a pin and slot pivotal connection between each door and its associate bolt, each bolt being adapted to engage behind the edge of the other discharge door in the loading position of the doors.

The foregoing specification signed at Essen, Germany, this 19th day of September, 1921.

PAUL KRÜGER.
